UNITED STATES PATENT OFFICE

JOHN F. TRITLE, OF ERIE, PENNSYLVANIA, ASSIGNOR TO GENERAL ELECTRIC COMPANY, A CORPORATION OF NEW YORK

ELECTRICAL RESISTOR

Application filed June 15, 1928. Serial No. 285,728.

My invention relates to electrical resistors, more particularly to resistors employed in the control of electrical apparatus, such as motors, and has for its object the provision 5 of an electrical resistor which is simple, compact and light in construction, and durable, effective and convenient in operation.

Although my invention has general application in the control of electrical apparatus it has particular application in the control of electric cars and locomotives. It is very desirable in equipments of this character where exceptional vibration occurs, that the electrical resistors employed be of a 15 rigid, strong, and durable construction. It is further desirable that they have large heat radiating surfaces and yet be light in weight.

Various forms of resistors have been proposed as substitutes for the ordinary heavy 20 cast grid, but it has often been found that their lack of rigidity is a serious limitation to their effectiveness since neighboring grids are in danger of coming into contact with each other. For this reason the various 25 forms of stamped grids have been furnished with stiffening means, as for example, stiffening rods or wires. These stiffening rods or wires, however, not only increase the cost of construction but also by contacting with the 30 resisting elements decrease their effective radiating surfaces. My invention, therefore, contemplates the provision of a resistor in which the advantages of large radiating surfaces are incorporated with those of light, 35 rigid and economic construction.

In carrying out my invention in one form thereof, I provide a resistor made up of a plurality of resistance units, each resistance unit of the resistor assembly being provided 40 with an insulated support on which a resistance ribbon is wound into a substantially flat coil with spaced turns, the ribbon having but a very small area in contact with the insulated support. I further enhance the rigidity 45 of the unit by providing separate supports for the terminals, the supports not only relieving the unit of the entire terminal load, but also permitting ready adjustment of the terminal connections.

50 For a more complete understanding of my

invention, reference should be had to the accompanying drawing in which Fig. 1 is a perspective view of the assembled resistor with portions broken away to illustrate certain structural details, Fig. 2 is an expanded 55 view of a portion of the resistor assembly showing the relation between the resistance units and the metallic spacers which serve as terminal supports, Fig. 3 is a diagrammatic representation of the units connected 60 in series, and Fig. 4 is a diagrammatic representation of the units connected in multiple.

Referring to the drawing, I have shown my invention in one form as applied to an 65 electrical resistor particularly applicable to car or locomotive control equipment. As shown, the resistor 10 comprises a plurality of resistance units 11 suitably mounted within a supporting casing 12. The casing 12 70 comprises metal end plates 13 and a top heat insulating plate 14 made of asbestos composition or the like, the casing 12 being provided with supporting brackets 15 suitably connected thereto and insulated therefrom 75 by insulators 16.

Referring particularly to Fig. 2, it will be observed that each resistance unit 11 comprises a light, resilient, metal ribbon made of a suitable electrical resistance material such 80 as an alloy of iron, aluminum and chromium. This ribbon is wound into a substantially flat coil 20 having the form of a flattened helix which has its turns spaced apart so that there is no danger of the various portions of the 85 ribbon coming into contact with each other. Each unit also comprises a suitable insulated support 21 which is provided for the coil 20, the support 21 being inserted within the coil substantially axially or centrally thereof and 90 being firmly gripped between the lengths forming the various convolutions due to the inherent resiliency of the metal from which the coil is formed. Thus, not only is the coil 20 supported at a plurality of points, but it 95 is also so supported that but a very small portion of its inner surface is in actual contact with the supporting member. In order that the insulated support 21 may be of rigid construction, a steel plate 22 is sandwiched be- 100

tween insulating strips 23, as for example mica strips, which in turn are gripped between the convolutions of the coil 20.

A metallic spacer 24, serving not only as a spacer but also as an electrical conductor, as will be explained, is inserted between each pair of units 11, the spacers 24 being insulated from the adjacent coils 20 by means of suitable insulating strips 25. Thus, the units 10 and spacers are arranged in alternate order within the resistor assembly. The upper end of each metallic spacer 24 is provided with a projecting portion 26 suitably apertured to receive an electrical terminal connection.

Referring to Figs. 2 and 3, it will be observed that the two terminals of each resistance coil 20 are brought out at opposite sides of its support 21, and that the upper terminal of the coil is connected, as by welding, to the 20 upper end of the spacer 24 positioned at that side of the unit and that the lower terminal of the coil is likewise connected to the lower end of the spacer 24 positioned at the other side of the unit. Thus, the adjacent coils 20 25 are connected in series, the spacers 24 serving as electrical conductors between them. It is pointed out that this construction permits all the terminal load to be carried directly by the spacers 24, all external loads 30 and strains thus being removed from the coils 20. Furthermore, this construction provides additional supporting means for the coils 20 since each coil in addition to being supported by its supporting member 21, which 35 is firmly gripped, is supported at its ends by being welded to the spacers.

In order that the units 11 and the spacers 24 may be supported, and formed into a rigid, compact, assembled construction, the supports 21 and the spacers 24 are provided at each end with an aperture 28 through which suitable insulated, supporting rods 30 may be passed. Referring to Fig. 1, it will be observed that the insulated rods 30 extend 45 throughout the entire length of the resistor assembly and are rigidly secured to the end plates 13 by means of nuts 31. Thus, the units 11 and the spacers 24 are rigidly and compactly mounted within the casing 12.

Suitable channel members 33 extend vertically within the casing 10 and are provided with apertures through which the insulated rods 30 pass, whereby the rigidity of the entire assembly is increased.

It is pointed out that the projecting portions 26 of each of the spacers 24 are at the top of the resistor assembly, thereby permitting all of the outside electrical connections to be brought in at the top thereof. This 60 construction greatly increases the convenience in making various adjustments of resistance.

Although Figs. 2 and 3 illustrate the units 11 connected in series, they may very conveniently be connected in multiple as shown

diagrammatically in Fig. 4. As shown, the two upper ends of a pair of adjacent coils 20 are connected to one end of a spacer 24 while the other ends of the two coils 20 are connected to the lower end of the succeeding spacer 24. It is to be understood that Fig. 4 is purely diagrammatical and that in either the series arrangement, shown in Fig. 3, or the multiple arrangement, shown in Fig. 4, all terminal connections are brought in at the top and the assembled structure is identical in each case.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention the scope of which is set forth in the annexed claims.

What I claim as new and desire to secure by Letters Patent of the United States is:

1. A resistor assembly comprising a plurality of resistance units, each unit comprising a flattened helix of metal ribbon wound flatwise, an insulating support disposed within said helix and in contact with a relatively small area of the inner surface of said ribbon, insulated metallic spacers between adjacent units to which terminals of the units are connected, and means for clamping said helices, supports, and spacers together to form a rigid assembly.

2. A resistor assembly comprising a plurality of resistance units, each unit comprising a substantially flat coil, an insulated support surrounded by said coil, insulated metallic spacers between adjacent units to which terminals of the units are connected, the said spacers being adapted to receive external connections at their corresponding ends, and means for clamping said coils, supports, and spacers together to form a rigid assembly.

3. A resistor assembly comprising a plurality of resistance units, each unit comprising a flat helix of metal ribbon wound flatwise, an insulated metallic support disposed within said helix and in contact with a relatively small area of the inner surface of said ribbon, insulated metallic spacers interposed between adjacent units to which terminals of the units are connected, the said spacers and supports being mounted parallel to each other, and means for supporting said helices, supports and spacers and holding the same in fixed relationship in the resistor assembly.

In witness whereof I have hereunto set my hand this 17th day of May, 1928.

JOHN F. TRITTLE.
